UNITED STATES PATENT OFFICE.

OSKAR ANTON WIBERG, OF FINSPOONG, SWEDEN, ASSIGNOR, BY MESNE ASSIGNMENTS,
TO AKTIEBOLAGET LJUNGSTROMS ANGTURBIN, OF STOCKHOLM, SWEDEN, A COR-
PORATION.

ELASTIC-FLUID TURBINE.

1,378,506.

Specification of Letters Patent. Patented May 17, 1921.

Application filed February 19, 1920. Serial No. 360,009.

To all whom it may concern:

Be it known that I, OSKAR ANTON WIBERG, a subject of the King of Sweden, residing at Finspong, Sweden, have invented 5 certain new and useful Improvements in Elastic-Fluid Turbines, of which the following is a specification.

The present invention relates to elastic-fluid turbines and specifically to that type 10 having a radial flow high pressure blade system, the parts of which revolve in opposite direction and also an axial flow low pressure blade system, the latter receiving steam from the former. In such a turbine 15 the blades of the radial flow system are mounted on rotor elements and extend axially. The blades of the axial flow system are mounted on separate rotor elements hereinafter referred to as wheels, which are 20 attached to the inner elements and extend radially.

The wheels are heat-treated to render them very strong and tough and if, in operation, they are subjected to the action of 25 high temperature steam, in such manner that a substantial increase in temperature results, their strength will be materially decreased. It is also important that the entire wheels be maintained at substantially 30 the same temperature to prevent stress being set up due to uneven heating. The object of the present invention is to provide an improved structure and arrangement in a turbine of the character referred to where- 35 in provision is made for effecting a flow of comparatively cool steam over portions of the wheels so as to prevent undue heating of the same and maintain the entire wheels at substantially constant temperature.

40 For a consideration of what I believe to be novel and my invention, attention is directed to the accompanying description and the claims appended thereto.

In the drawing, the figure is a radial sectional view of a portion of an elastic-fluid turbine embodying my invention. The drawing shows the left-hand side of a turbine and a part of the right-hand side and it will be understood that the two sides are 45 alike, the right-hand side being a duplicate of the left-hand side.

50 Referring to the drawing, 5 and 5^a indicate inner rotating elements, carrying rings of interleaving blades 6 and 6^a, respectively, 55 through which elastic-fluid flows radially

outward thereby causing elements 5 and 5^a to rotate in opposite directions. Blades 6 and 6^a are connected to elements 5 and 5^a by suitable expansion rings 8 and 8^a, this being now a known form of connection in 60 this type of turbine. The inner rotating element 5 is carried by a stub shaft 9 which, in turn, is carried by a main shaft (not shown). Inner rotating element 5^a is carried by similar stub shaft (not shown). In 65 the description following I will describe the left-hand side of the turbine only, it being understood, as above stated, that the right-hand side is a duplicate thereof. Surrounding inner rotating element 5 is an in- 70 termediate rotating element 10 fastened to element 5 by expansion ring 11. Carried by intermediate rotating element 10 are axially extending blade rings 12, with which interleave blade rings 12^a of the right-hand side 75 of the machine. Connected to intermediate rotating element 10 by expansion ring 13 is a wheel 14, which carries a ring of radially extending blades 15. Carried by the inner side of wheel 14 are axially extending blade 80 rings 16, which interleave with blade rings 16^a of the right-hand side of the machine. Blade rings 16 are connected to wheel 14 by expansion rings 17. Elements 5 and 10 and wheel 14, with their attached rings of 85 buckets, form as a whole one rotor of the turbine. Fastened to the surrounding casing wall 19 is a holder 20, which carries a ring of nozzles 21 for directing elastic fluid to blade ring 15 and depending from nozzle 90 ring 21 is an annular wall 22, which defines one side of a steam space for receiving the exhaust from the radial flow bucket rings 16 and 16^a and directing it to nozzles 21. Between the bore of wall 22 and the outer edge 95 of the outermost ring of buckets 16^a is a suitable packing strip 22^a.

The adjacent stationary side wall of the turbine casing is indicated at 24, and between it and the stub shaft 9 is a suitable 100 shaft packing 25 to prevent leakage between the shaft and the casing. Projecting from side wall 24 are two concentric annular walls 26 and 27, which define steam chambers 28 and 29. Elastic fluid is admitted to 105 chamber 28 through a supply conduit 30, and from chamber 28 it passes through openings 31 to the radial flow blade system. Chamber 29 may be supplied with elastic fluid from chamber 28 through suit- 110

able valves (not shown), or may be supplied with elastic fluid through a separate conduit similar to conduit 30. From chamber 29 elastic fluid is supplied through passages 32 and 33 to an intermediate point in the radial flow blade system. The admission of elastic fluid to an intermediate point in the turbine is for the purpose of getting increased power from the machine as is well understood. Between the rotor and the adjacent casing wall is arranged a packing and axial balancing means comprising two disks 35 and 36. Disk 35 is connected to inner rotating element 5 by means of expansion rings 37 and disk 36 is connected to walls 26 and 27 by means of expansion rings 38. Between disks 35 and 36 are interleaving packing rings 39 which are carried by said disks. It will be seen that disk 35 turns within the rotor while disk 36 is stationary. Surrounding disk 36 and located within the bore of wheel 14 is a shield ring 40, which is supported in the spaced relation to disk 36 by projections 41. Shield ring 40 is spaced from the bore of wheel 14 so as to leave an annular passage 42 between them. The right-hand inner surface of shield ring 40 is beveled so that it forms with the peripheral surfaces of disks 35 and 36 a Venturi-shaped annular passage through which elastic fluid leaking between the balancing disks 35 and 36 is discharged. Such leakage elastic fluid will have a comparatively high temperature and one of the functions of ring 40 is to protect the bore of wheel 14 from this elastic fluid.

The operation of a turbine as shown is well understood, elastic fluid flowing first through the radial flow portion of the machine and then dividing and flowing through the two axial flow portions, each of which comprises a ring of nozzles 21 and a wheel 14.

It will be noted that between the periphery of the balancing disk 35 and expansion ring 13 is an annular chamber designated 43, and when the turbine is operating elastic fluid issuing from the packing means between balancing disks 35 and 36 and discharging through the passage between ring 40 and the periphery of balancing disk 36, creates a suction after the manner of the ejector which acts to draw elastic fluid which may be present in the chamber 43 out of such chamber and discharge it into the casing of the turbine which, as is well understood, is connected with the condenser. This reduces the pressure in chamber 43 and as a result exhaust elastic fluid flows through the annular passage 42 between ring 40 and the bore of wheel 14 into the chamber 43, from whence it is continuously removed by the ejector action referred to. There is thus set up a continuous flow of 65 exhaust fluid through the annular passage

42 to chamber 43 and thence out between ring 40 and the periphery of balancing disk 36, which serves to protect the bore of wheel 14 from the hot elastic fluid issuing from between the balancing disks 35 and 36 and 70 also to extract heat from the wheel 14 to cool it. It will thus be seen that I utilize the leakage of elastic fluid from the packing between the balancing disks to create a suction for drawing cooling fluid through the 75 bore of wheel 14. It will also be noted that I utilize as cooling medium elastic fluid after it has exhausted from bucket ring 15 and has, therefore, been expanded down to the lowest pressure and temperature which 80 it reaches before exhausting to the condenser. I thus provide a most efficient and economic cooling means for the impulse wheel 14 and one which tends to maintain the portion of the wheel adjacent its bore 85 at substantially the same temperature as the remainder of the wheel.

In accordance with the provisions of the patent statutes, I have described the principle of operation of my invention, together 90 with the apparatus which I now consider to represent the best embodiment thereof; but I desire to have it understood that the apparatus shown is only illustrative, and that the invention can be carried out by other 95 means.

What I claim as new and desire to secure by Letters Patent of the United States, is,—

1. The combination with an elastic-fluid 100 turbine having a rotor, of means forming an ejector for causing cooling fluid to circulate adjacent said rotor.
2. In an elastic-fluid turbine having a rotor element and a packing means, means 105 actuated by elastic fluid issuing from said packing means for causing cooling fluid to circulate adjacent said rotor.
3. In an elastic-fluid turbine having a rotor element provided with a bore and packing means, means defining a passage 110 through said bore through which cooling medium is drawn by the ejector action of elastic fluid leaking from said packing.
4. In an elastic-fluid turbine comprising 115 a member having axially extending buckets thereon and a wheel carried by said member and having radially extending buckets thereon, said wheel having an enlarged bore, means defining a path for conducting elastic fluid for cooling purposes from the exhaust side of said wheel inwardly through 120 said bore.
5. In an elastic-fluid turbine having a rotor comprising an inner radial flow portion 125 and an outer axial flow portion having a bore, and balancing disks, means actuated by the issuing of elastic fluid from said balancing disks for causing cooling medium to flow through said bore to cool the rotor, 130

6. In an elastic-fluid turbine having a rotor comprising two members connected to each other and carrying bucket elements, one of said members being located to one side of the other and having an enlarged bore, means defining a path for conducting elastic fluid through said bore to cool said one member, and means for causing elastic fluid to flow through said path.
- 10 7. In an elastic-fluid turbine, the combination of oppositely rotating elements having interleaving blades, a bladed wheel having an enlarged bore connected to each element, a pair of balancing disks for each element located at the bore of its wheel, and means actuated by the issuing of elastic fluid from between said balancing disks for causing a cooling means to flow through the bore of such wheel.
- 15 8. In an elastic fluid turbine having a rotor element provided with a bore, and packing means, means defining a passage through said bore through which cooling medium is drawn from the exhaust side of the rotor element inwardly through said bore by the ejector action of elastic fluid leaking from said packing.
- 20 9. In an elastic fluid turbine having a rotor comprising an inner radial flow portion and an outer axial portion having a bore, and balancing disks, means actuated by the issuing of elastic fluid from said balancing disks for causing cooling medium to flow from the exhaust side of said outer axial flow portion of the rotor inwardly through its bore to cool the rotor.

In witness whereof, I have hereunto set my hand this 30th day of October, 1919.

OSKAR ANTON WIBERG.
